(57) CLAIM

The ornamental design for a bottle cap, as shown and described.

DESCRIPTION

FIG. 1 is a top and first side perspective view of a bottle cap showing my new design;

FIG. 2 is a bottom and first side perspective view thereof;

FIG. 3 is a first side elevational view thereof;

FIG. 4 is a second side elevational view thereof;

FIG. 5 is a third side elevational view thereof;

FIG. 6 is a fourth side elevational view thereof;

FIG. 7 is a top elevational view thereof;

FIG. 8 is a bottom elevational view thereof.

FIG. 9 is a top and first side perspective view of a second embodiment of a bottle cap showing my new design;

FIG. 10 is a bottom and first side perspective view thereof;

FIG. 11 is a first side elevational view thereof;

FIG. 12 is a second side elevational view thereof;

FIG. 13 is a third side elevational view thereof;

FIG. 14 is a fourth side elevational view thereof;

FIG. 15 is a top elevational view thereof;

FIG. 16 is a bottom elevational view thereof.

FIG. 17 is a top and first side perspective view of a third embodiment of a bottle cap showing my new design;

FIG. 18 is a bottom and first side perspective view thereof;

FIG. 19 is a top elevational view thereof;

FIG. 20 is a bottom elevational view thereof.

FIG. 21 is a first side elevational view thereof;

FIG. 22 is a second side elevational view thereof;

FIG. 23 is a third side elevational view thereof;

FIG. 24 is a fourth side elevational view thereof;

FIG. 25 is a top and first side perspective view of a fourth embodiment of a bottle cap showing my new design;

FIG. 26 is a bottom and first side perspective view thereof;

FIG. 27 is a top elevational view thereof;

FIG. 28 is a bottom elevational view thereof.

FIG. 29 is a first side elevational view thereof;

FIG. 30 is a second side elevational view thereof;

FIG. 31 is a third side elevational view thereof;

FIG. 32 is a fourth side elevational view thereof;

FIG. 33 is a top and first side perspective view of a fifth embodiment of a bottle cap showing my new design;

FIG. 34 is a bottom and first side perspective view thereof;

FIG. 35 is a top elevational view thereof;

FIG. 36 is a bottom elevational view thereof.

FIG. 37 is a first side elevational view thereof;

FIG. 38 is a second side elevational view thereof;

FIG. 39 is a third side elevational view thereof; and,

FIG. 40 is a fourth side elevational view thereof.

The broken lines in FIGS. 2, 8, 10, 16, 18, 20, 26, 28, 34, and 36 are shown for the purpose of illustrating parts of the bottle cap that form no part of the claim.
